UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

CAR-SEAT.

No. 894,811.

Specification of Letters Patent.

Patented Aug. 4, 1908.

Application filed April 18, 1907. Serial No. 368,820.

To all whom it may concern:

Be it known that I, EDWARD G. BUDD, a citizen of the United States, residing at Philadelphia, in the county of Philadelphia and 5 State of Pennsylvania, have invented a new and useful Improvement in Car-Seats, of which the following is a specification.

This invention relates to seats for use in railway cars and has reference particularly to 10 the type of seating in which two seats are built together, back to back, as commonly employed in sleeping cars.

The object of the invention is to effect certain improvements in the construction of 15 car-seats of this type, to the end that a structure is provided which possesses great strength, which is of attractive appearance, and which is constructed largely of metallic parts.

20 The preferred embodiment of the invention is illustrated in the accompanying drawings, in which

Figure 1 is a transverse section through the two seats, immediately inside the aisle- 25 end thereof; Fig. 2 is a section on line 2—2 of Fig. 1; Fig. 3 is a transverse section on line 3—3 of Fig. 2, showing the wall-end of one of the seats; Fig. 4 is a detail view in perspective, showing a portion of the wall- 30 end of one of the seats; Fig. 5 is an enlarged section of a portion of the structure shown in Fig. 2; Fig. 6 is a section on line 6—6 of Fig. 1; Fig. 7 is a section on line 7—7 of Fig. 1; Fig. 8 is a sectional view, showing in elevation the means for supporting one of the 35 detachable side-pads; Fig. 9 is a section on the line 9—9 of Fig. 1, broken away in part; Fig. 10 is a perspective view of one of the side-pads; and Fig. 11 is a perspective view 40 of one of the holders for the side pads.

Referring to these drawings, the seat-end at the aisle-end of the seat structure consists of two sheet-metal plates spaced apart by a short distance but secured together, this 45 seat-end being connected to the wall of the car by suitable braces, including a partition lying between the two seats.

The outer plate of the seat-end is indicated by the numeral 1 and the inner plate by the 50 numeral 2. The outer plate 1 is cut to form two legs at the bottom thereof, an enlarged portion above these legs extending outwardly in opposite directions to cover the ends of the seat-cushions, and an upwardly extend-

ing central portion to cover the ends of the 55 back-cushions. The inner plate 2 is similarly shaped at the lower portion thereof, but does not extend upwardly opposite the ends of the back-cushions; instead, the inner plate 2 is cut away along the line 3, 3 (Fig. 1) 60 to provide spaces in which the detachable side-pads hereinafter described are mounted. The two plates 1 and 2 are secured together parallel to each other but spaced apart by a short distance by spacers 4, 4 (Figs. 1, 2 and 65 6). These spacers are of U-shaped cross-section and the flange at one side thereof is secured by rivets 5 to the inner plate 2. The flange at the other side of the spacer is secured to the plate 1, but rivets are not 70 employed for this purpose, as rivet heads showing on the outer side of the seat-end would detract from the appearance of the seating; this flange of the spacer 4 is therefore provided with enlarged pads 6 at both 75 ends thereof and these pads are soldered over the entire outer face thereof to the inner side of the plate 1. The two plates 1 and 2 are thus secured firmly together at the proper distance one from the other, by the four 80 spacers 4.

At the bottom of the two plates 1 and 2, the material is cut away to form the two legs 7 and 8. The lower edge of the seat-end between these legs is closed by a sheet-metal 85 strip 9 (Figs. 1 and 9) secured at one edge to the plate 1 and at the other edge to the plate 2. In order to avoid rivet heads showing on the outside of the seat-end, the plate 1 between the legs 7 and 8, is provided with an 90 inwardly-turned flange 10 (Fig. 9) and one edge of the strip 9 is riveted to this flange. At its other edge, the strip 9 has a flange 11 turned at a right angle to the body of the strip, so as to lie alongside the edge of the 95 plate 2, and this flange is riveted to the plate 2, as shown at 12 Fig. 2.

The lateral edges of the seat-end are closed by edge-pieces 13 and 14, these being either castings or sheet-metal parts of substantially 100 semicircular cross-section, as shown in Fig. 6. The pieces 13 and 14 are curved to conform to the curvature of the lateral edges of the plates 1 and 2, and are of such size that their lateral edges fit between the edges of the 105 plates 1 and 2, as shown in Fig. 6. When the plates and the edge-piece 14 are assembled in the proper relative positions, they are riveted

together as shown at 15 (Fig. 6). Both of the lines of rivets 15, however, are concealed, in order not to detract from the appearance of the seat-end, and also to prevent the 5 clothing from catching upon these rivets. For this purpose, molding strips 16 are provided, curved longitudinally to correspond to the curvature of the lines of rivets and bent laterally to provide central portions 10 overlying the rivets and edge portions bearing against the plates of the seat-end. The edge portions of each of the molding strips 16 are soldered to the plate of the seat-end, so that the molding strips overlie and 15 conceal the rivets. The edges of the plates 1 and 2 are rounded off as shown in Fig. 6 so that the inner and outer surfaces of the seat-end round neatly into the surface of the edge-strips 13 and 14. At its lower end, the metal 20 of each of the strips 13 and 14 is rounded over to close the end of the strip (Figs. 1 and 9), thus making the leg of the seat of attractive appearance. A suitably-shaped foot may 25 be provided fitting within the end of each of the legs and this may be secured to the floor if desired.

Riveted to the plate 2 of the seat-end at the center thereof, is a bracket 17 (Figs. 1 and 2), and a similar bracket 17' is secured 30 to the wall of the car in horizontal alinement with the bracket 17. Extending between and secured upon these brackets are two angular bars 18 for positioning a partition 19 vertically disposed between the two seats and 35 extending upwardly in the plane of the length of the seats to the top thereof. This partition is preferably formed of tongue-and-groove boards and is sheathed on either side with sheet-metal 20, this construction serving 40 to prevent, to a very large extent, vibration and the reverberation of sound.

Secured to the plate 2 of the seat-end and to the partition 19 by suitable bolts or rivets, are two castings 21, each having a horizontally disposed portion for supporting one end 45 of a seat-cushion and a pivoted bracket 22 on which and a similar bracket at the wall end of the seat the lower member of the frame of the back-cushion rests, to support the back 50 cushion in position.

In seating of this type, it is desirable to provide upholstered side-pads at the side of the seat, one supported upon the seat-end and the other upon the wall of the car. The side- 55 pad at the aisle-end of the seat is arranged to be detachably mounted in the space provided by cutting away the inner plate 2 of the seat-end along the line 3, 3. Each of the two side-pads at the aisle-end of the seat is supported 60 by two holders 23, shown in Figs. 1, 5 and 8, and by a support coacting with the lower edge of the side-pad. Each of the holders 23, shown in perspective in Fig. 11, is a casting having outwardly extending ears 24 at 65 the top thereof, riveted to the overlying struc-

ture, as shown in Figs. 1 and 8, and ears 25 which are soldered to the inner side of the plate 1 in order to avoid the use of rivets which would show from the exterior of the seat-end. The holder also has a vertical 70 wall 26 (Fig. 5) at the inner side thereof, provided with a slot extending downwardly from its upper edge. The plate 1 is provided with an inwardly extending flange 27 along the edge of the upper portion thereof, extending 75 from the ends of the frame-pieces 13 and 14 to the top of the plate. A strip of U-shaped sheet-metal 28, curved in the direction of its length, is secured by means of rivets along this edge, overlying the flange 27 and extending 80 downwardly a short distance along the body of the plate 1. (Figs. 2, 5 and 8.) The ears 24 of the holders 23 are secured by rivets to this U-shaped strip 28, and the strip is cut away directly over the slots in the walls 26 of 85 the holders, in order not to obstruct the passage of a headed stud into the slots. The upper edge of the inner plate 2 of the seat-end along the horizontal portions of the line 3, is provided with flanges 29 (Figs. 2 and 5) 90 turned inwardly of the seat-end, and secured to each of these flanges is a sheet-metal strip 30, having at its inner edge a longitudinal groove 31.

Each of the side-pads which are secured to 95 the seat-end consists of a sheet-metal plate 32 corresponding in shape to the portion of the plate 1 extending above the plate 2. At its lower edge, the plate 32 has an integral inwardly-extending flange 33 (Figs. 2 and 5), 100 with a downwardly turned edge 34 adapted to be received in the groove 31 in the sheet-metal strip 30.

Secured to the plate 32 by means of rivets in positions to coact with the holders 23, are 105 castings 35 carrying on their inner faces headed studs 36 adapted to enter within the slots in the holders 23 and to coact with the walls thereof to secure the side-pad in position. 110

A U-shaped sheet-metal strip 37, curved to correspond to the curvature of the upper edge of the seat-end, is secured by means of rivets 38 (Fig. 5) to the edge of the plate 32 of the side-pad. Riveted to the other edge 115 of the strip 37, is a sheet-metal strip 39 of angular cross-section. The U-shaped strip 37 is of such size that the vertical web of the angular strip 39 is in substantial alinement with the plate 1, and the strip 39 is of such 120 size that the horizontal web thereof lies close to the upper face of the U-shaped strip 28. In order to stiffen the side-pad 32, a plurality of metallic stiffening pieces 40 of angular cross-section are provided, riveted to the 125 plate 32 on the inner side thereof. Near the upper edge of the side-pad, the metal of the plate 32 is pressed out to form a raised portion 41 (Figs. 1, 2, 7 and 10), the height of the raised portion 41 being substantially the 130

same as the thickness of the upholstery material to be applied to the surface of the side-pad. This raised portion 41 has a key-hole slot 42 cut therein, to receive a stud at one end of the head-roll of the seat, such as that shown in my application, Serial Number 382,133, filed on or about July 5, 1907. By raising the metal to form the portion 41, the head-roll is more securely supported, the necessity of providing an opening through the upholstery is avoided and the edge of the covering of the side-pad about the opening for the stud can be readily finished to form a neat structure and one which will wear well. The keyhole slot in the raised portion 41 on the side-pad and a similar keyhole slot in the structure at the wall end of the seat constitute devices for pivotally supporting a head-roll constructed as shown in my application above mentioned, this head-roll being provided with studs at its ends, the sides of which are flattened. These studs normally lie in the circular portions of the keyhole slots and the head-roll may be turned on these studs as pivots. When the head-roll has been swung to an elevated position, the studs will drop into the slots, extending outwardly from the circular portions of the keyhole slots, so as to hold the head-roll in this position.

The flange at the upper edge of the side-pad, consisting of the curved edge of the plate 32 and the flange at the lateral edge of the U-shaped strip 37, is perforated by a line of holes as shown in Fig. 10 to facilitate securing the upholstery and covering material 32' of the side-pad to the metallic frame thereof, and the strip 37 is similarly perforated by a line of holes down the center thereof as shown in Fig. 5, for the same purpose. When the upholstery material has been applied to and secured upon the outer face of the side-pad, the latter is mounted in position by passing the studs 36 into the slots in the vertical walls 26 of the holders 23, and as these studs reach the bottom of the slots, the downwardly extending rib 34 at the edge of the flange 33 enters the groove 31 in the strip 30 secured to the inner plate 2 of the seat-end. The side-pad is thus held securely in position. The surface of the cushion supported upon the horizontal portion of the casting 21 extends up slightly above the lower edge of the side-pad, and similarly the surface of the back-cushion extends out beyond the rear edge of the side-pad. The strips 37 and 39 are preferably extended at their lower ends slightly beyond the forward vertical edge of the side-pad and plate 32 may have an outwardly extending portion thereon directly under these strips, as shown at 38' (Fig. 10). A projection is thus provided on each side-pad which directly overlies the upper end of one of the edge-pieces 13 and 14. The strips 37 have

upholstery material secured thereon as shown to finish the upper edge of the combined seat-end and pad and form arm-rests.

At the wall-end of the seat, a sheet-metal plate 43, flanged at its edges, is secured to the wall, as shown in Figs. 2 and 3, angular metallic strips 44 being provided around the edges of plate 43 except at the bottom thereof, one web of each of these strips being secured to the flange upon the plate 43 and the other web secured to the wall. Riveted to the plate 43 near the top thereof, is a metallic plate 44' having the central portion thereof raised to correspond to the raised portion 41 on the detachable side-pad at the aisle-end of the seat, and this raised portion has a keyhole slot therein, similar to the slot 42 and for the same purpose. A sheet-metal piece 45 curved longitudinally is secured by means of rivets to the plate 43, as shown in Figs. 2, 3 and 4, and a similar sheet-metal piece 46 is secured to the forward, vertically disposed edge of the plate 43, its upper end abutting and alining with the forward end of the arm-rest 45. A short sheet-metal strip 47 overlaps the joint between the pieces 45 and 46 and is secured thereto to hold them in proper relative position. The piece 46 tapers from its upper edge downward, and the piece 45 from its forward edge backward, as shown in Figs. 3 and 4. The plate 43 is perforated with a line of holes 48, to facilitate securing the upholstery and covering material 43' to the plate.

Extending between the seat-end and the wall directly overlying the upper edge of the partition 19, is a rail 49 having a groove in the upper edge thereof. The inner end of this rail is secured to the wall of the car by means of a bracket 50. The outer end of the bar is carried by a plate 51, which is secured to the plate 1 of the seat-end by means of screws extending from the inside of the plate 1 through the plate and into the plate 51. Plate 51 has a vertically disposed slot cut therein, in which is adapted to reciprocate a headed stud 52 secured at its inner end to a latch 53, the upper end of which is adapted to coact with a part on a removable partition such as is now commonly used in sleeping cars, which may be mounted in position with its lower edge resting in the groove in the rail 49, this removable partition extending upward from the rail to the roof of the car.

I have illustrated and described herein the preferred embodiment of my invention, but I do not wish to be understood as limited to this particular construction since it may be modified in many respects. Also, some of the features of my invention may be employed in a structure adapted for the same or similar uses in which other features of the invention are omitted. All such modifications of the invention, I consider within its

scope and I aim to cover them by the terms of the claims appended hereto.

Having now described my invention, what I claim as new therein and desire to secure 5 by Letters Patent is as follows:—

1. The combination of a seat-end consisting of two sheet-metal plates secured together parallel to but separated from each other, a car wall, a central vertical partition 10 connecting the seat-end with the wall of the car, means on the seat-end and wall for supporting the ends of two seat-cushions and for supporting the ends of two back-cushions in substantially vertical planes at the 15 adjacent edges of the seat-cushions, and devices on the seat-end and wall for pivotally supporting head-rolls above the back-cushions, said partition extending above said devices for supporting the head-rolls, substantially as set forth.

2. The combination of a seat-end consisting of two sheet-metal plates secured together parallel to but separated from each other, said plates being cut to form legs at 25 the bottom thereof, and an enlarged body portion above said legs and extending outwardly in opposite directions therefrom and one of said plates having a portion extending upwardly from the center thereof above the 30 upper edge of the other of said plates, means connecting the seat-end to the wall of a car, two seat-cushions and two back-cushions, and means on the seat-end for supporting said seat-cushions and for supporting 35 said back-cushions in substantially vertical planes at the adjacent edges of the seat-cushions, substantially as set forth.

3. The combination of a seat-end consisting of two sheet-metal plates secured together parallel to but separated from each other, a car wall, members secured to and connecting the seat-end and wall, the means 40 securing said members to the seat-end being concealed, supports on the seat-end and wall 45 for holding two seat-cushions and for holding two back-cushions in substantially vertical planes at the adjacent edges of the seat-cushions, the means for securing said supports to the seat-end being concealed, and 50 devices on the seat-end and wall for pivotally supporting a head-roll above each of said back-cushions, substantially as set forth.

4. A seat-end consisting of an inner and an outer sheet-metal plate cut to form legs 55 at the bottom thereof, and means for closing the lower edge of the seat-end between said legs consisting of a sheet-metal strip secured to the edges of the plates, the means for securing the strip to the outer plate being concealed, substantially as described.

5. A seat-end consisting of an inner and an outer plate cut to form legs at the bottom thereof, said outer plate having an integral, inwardly extending flange at the bottom 60 thereof between the legs thereon, and means

for closing the lower edge of the seat-end between said legs consisting of a sheet-metal strip secured at its edges to said flange and to the inner plate, substantially as set forth.

6. A seat-end formed of two sheet-metal 70 plates secured together parallel to but separated from each other, a metallic strip closing the edge of the seat-end, means for securing the edges of said strips to the edges of said plates, and devices overlying and concealing 75 said securing means, substantially as set forth.

7. A seat-end consisting of two sheet-metal plates secured together parallel to but separated from each other, said plates being 80 cut to form a base portion, an enlarged body portion above said base portion and extending outwardly in opposite directions therefrom and an upwardly extending central portion, metallic strips closing the edges of 85 the seat-end along said base and enlarged portions, and means for securing the edges of said strips to the edges of said plates, substantially as set forth.

8. A seat-end formed of two sheet-metal 90 plates secured together parallel to but separated from each other, a metallic strip closing the edge of the seat-end, means for securing the edges of the strip to the edges of said plates, and a metallic molding secured to the 95 seat-end and concealing said securing means, substantially as set forth.

9. A seat-end formed of two sheet-metal plates secured together parallel to but separated from each other, a metallic strip of U- 100 shaped cross-section closing the edge of the seat-end, a line of rivets securing each of the edges of said strip to the edge of one of said plates, and a metallic molding soldered to each of said plates and overlying the rivets 105 extending therethrough, substantially as set forth.

10. The combination of a car-wall, a seat-end formed of two sheet-metal plates secured together parallel to but separated from each other, a wooden partition sheathed in sheet-metal secured at its ends to said seat-end and said wall, means on said seat-end for supporting a seat-cushion on either side of said partition, and means on said seat-end for supporting two back-cushions in substantially vertical planes at the adjacent edges of said seat-cushions, substantially as set forth.

11. The combination of a car-wall, a seat-end formed of two sheet-metal plates secured together parallel to but separated from each other, said plates being cut to form a base portion, an enlarged body portion above the base portion and extending outwardly in opposite directions therefrom and an upwardly extending central portion, a rail connecting the car-wall and the upper portion of the seat-end, a latch movable to carry its end above the rail, and an operating device for said latch, substantially as set forth.

12. A metallic seat-end consisting of inner and outer sheet-metal plates secured together parallel to but separated from each other, each of said plates being cut to form a base portion and an enlarged body portion above the same and said outer plate having an integral upwardly extending portion above the body portion thereof and above the upper edge of the inner plate, substantially as set forth.

13. The combination of a metallic seat-end, supports for the end of seat- and back-cushions secured thereto, and a side-pad mounted on said seat-end and consisting of a sheet-metal plate provided with flanges at its edges and upholstery material secured thereon, substantially as set forth.

14. The combination of a seat-end, supports for the end of seat- and back-cushions secured thereto, a combined arm-rest and side-pad consisting of a sheet-metal frame and upholstery material secured thereon, and means for detachably mounting said pad and arm-rest upon said seat-end, with the arm-rest overlying the edge of the seat-end, substantially as set forth.

15. The combination of a seat-end consisting of inner and outer sheet-metal plates secured together parallel to but separated from each other, said inner plate being cut away to a smaller size than the outer plate, and a side-pad mounted on said seat-end in the space formed by the cutting away of said inner plate, substantially as set forth.

16. The combination of a seat-end consisting of inner and outer sheet-metal plates each having a base portion and an enlarged portion above the same and said outer plate having an upwardly extending portion above the upper edge of said inner plate, means on said seat-end for supporting seat- and back-cushions, and a side-pad detachably mounted on said seat-end opposite the upwardly extending portion of said outer plate, substantially as set forth.

17. The combination of a metallic seat-end, supports for seat- and back-cushions secured thereto, a combined arm-rest and side-pad consisting of a metallic frame, a metallic strip secured along one edge thereof, and upholstery material secured over said frame and strip, and studs and slotted members on the seat-end and pad for detachably mounting the pad upon the seat-end, substantially as set forth.

18. The combination of a metallic seat-end consisting of inner and outer sheet-metal plates secured together parallel to but separated from each other, supports for seat- and back-cushions secured thereto, a side-pad consisting of a metallic frame and upholstery material secured thereon, and members on the pad and seat-end for detachably mounting the pad upon the seat-end, the member on the seat-end being soldered to the inner

side of said outer plate, substantially as set forth.

19. The combination of a seat-end consisting of an inner and an outer plate secured together, said outer plate having an integral upwardly extending portion, supports for seat- and back-cushions secured to said seat-end, and an upholstered side-pad supported on the upper edge of said inner plate and extending upwardly therefrom opposite the upwardly extending portion of said outer plate, substantially as set forth.

20. The combination of a metallic seat-end, supports for seat- and back-cushions secured thereto, and a side-pad mounted on said seat-end and consisting of a sheet of metal, metallic strips secured to the edges thereof, and upholstery material secured thereto, substantially as set forth.

21. The combination of a metallic seat-end, supports for seat- and back-cushions secured thereto, and a side-pad mounted on said seat-end and consisting of a sheet of metal, metallic stiffening pieces secured to one side thereof and upholstery material secured to the other side thereof, substantially as set forth.

22. The combination of a metallic seat-end, and a side-pad secured thereto consisting of a metallic frame, upholstery material secured thereto and a flange on the frame overlying the upper edge of the seat-end, substantially as set forth.

23. The combination of a metallic seat-end, and a side-pad secured thereto consisting of a sheet-metal plate having an integral raised portion thereon and an opening in said raised portion for the support of upholstery devices, substantially as set forth.

24. The combination of a metallic seat-end and a side-pad secured thereto consisting of a sheet-metal plate having a raised portion thereon and upholstery material secured on said plate adjacent to said raised portion and of substantially the same thickness as the height of said raised portion, substantially as set forth.

25. The combination of a car-wall, a metallic seat-end, means connecting the seat-end and said wall, a metallic plate flanged at its edges secured to the car-wall and upholstery material secured upon said plate, substantially as set forth.

26. The combination of a car-wall, a metallic seat-end, means connecting the seat-end and said wall, a metallic plate secured to the car-wall, a smaller plate secured to said plate and having a raised portion therein, and upholstery material secured upon said first-named plate adjacent to said raised portion and of substantially the same thickness as the height of said raised portion, substantially as set forth.

27. The combination of a car-wall, a metallic seat-end, means connecting the seat-

end and said wall, a metallic plate secured to the car-wall, a sheet-metal piece curved transversely and secured in a horizontal position to one edge of said plate, and upholstery material secured on said plate, substantially as set forth.

28. The combination of a car-wall, a metallic seat-end, means connecting the seat-end and said wall, a metallic plate secured to the car-wall and having a horizontal upper edge and a vertically disposed forward edge, and sheet-metal pieces curved transversely and secured to said plate one adjacent to said horizontal edge and the other adjacent to said vertically disposed edge, substantially as set forth.

29. The combination of a car-wall, a metallic seat-end, means connecting the seat-end and said wall, a metallic plate secured to said wall parallel to but separated from said wall and upholstery material secured upon said plate, substantially as set forth.

30. The combination of a car-wall, a metallic seat-end, means connecting the seat-end and said wall, and combined arm-rests and side-pads secured to the seat-end and car-wall, each consisting of a metallic plate, a metallic arm-rest strip secured thereto and upholstery material secured over the plate and strip, substantially as set forth.

31. A seat-end consisting of two sheet-metal plates, and spacers securing said plates together parallel one to the other but spaced apart, each of said spacers having en-

larged pads at one of the lateral edges secured by solder to the outer one of said plates, substantially as set forth.

32. The combination of a seat-end consisting of inner and outer sheet-metal plates, secured together, said inner plate being cut away to a smaller size than the outer plate and a combined arm-rest and side-pad mounted on said seat-end in the space provided by the cutting away of said inner plate, substantially as set forth.

33. The combination of a seat-end, supports for seat- and back-cushions, and a combined arm-rest and side-pad mounted on the seat-end with said arm-rest overlying the edge of the seat-end, substantially as set forth.

34. The combination of a seat-end consisting of inner and outer sheet-metal plates secured together, said inner plate being cut away to a smaller size than the outer plate, supports for seat- and back-cushions, and a combined upholstered arm-rest and side-pad having a metallic support mounted on said seat-end in the space provided by the cutting away of said inner plate with said arm-rest overlying the upper edge of said outer plate, substantially as set forth.

This specification signed and witnessed this 4th day of March, 1907.

EDWARD G. BUDD.
